UNITED STATES PATENT OFFICE

107,895

DESIGN FOR A COMFORTABLE

Janet May, New York, N. Y.

Application November 10, 1937, Serial No. 72,741

Term of patent 3½ years

To all whom it may concern:

Be it known that I, Janet May, a citizen of the United States of America, residing in New York city, in the Borough of Manhattan, county and State of New York, have invented a new, original, and ornamental Design for a Comfortable, of which the following is a specification, reference being had to the accompanying drawing, forming part thereof, wherein,

The figure is a plan view of a comfortable showing my new design.

I claim:

The ornamental design for a comfortable, substantially as shown.

JANET MAY.
